(57) **CLAIM**

The ornamental design for modifiable jewelry, as shown and described.

DESCRIPTION

FIG. 1 is a front isometric view of a modifiable jewelry showing our new design;

FIG. 2 is a rear isometric view thereof;

FIG. 3 is a front elevation view thereof;

FIG. 4 is a front elevation view thereof, with the inner portion of the jewelry shown rotated 180 degrees;

FIG. 5 is a rear elevation view thereof, with the inner portion of the jewelry shown rotated 180 degrees;

FIG. 6 is a rear elevation view of FIG. 3;

FIG. 7 is front elevation view of the inner portion of the modifiable jewelry, shown removed for completeness of illustration;

FIG. 8 is a front elevation view of the outer portion of the modifiable jewelry, shown separately for completeness of illustration;

FIG. 9 is a rear elevation view of the inner portion of the modifiable jewelry, shown removed for completeness of illustration;

FIG. 10 is a rear elevation view of the outer portion of the modifiable jewelry, shown separately for completeness of illustration;

FIG. 11 is a top plan view of FIG. 1;

FIG. 12 is a bottom plan view thereof;

FIG. 13 is a side elevation view thereof; and,

FIG. 14 is an opposite side elevation view thereof.
